(Cl. D90—16)

To all whom it may concern:

Be it known that we, Samuel Crane, residing in Brooklyn, county of Kings, and State of New York, and Stephen D. Kent, residing in the county of Queens, city and State of New York, both citizens of the United States, have invented a new, original, and ornamental Design for a Bicycle Seat Cover, of which the following is a specification, reference being had to the accompanying drawings, forming part thereof.

Fig. 1 is a perspective view of a bicycle seat cover showing my new design; and

Fig. 2 is a cross section thereof taken on line 2—2 of Fig. 1.

We claim:

The ornamental design for a bicycle seat cover, as shown and described.

SAMUEL CRANE.
STEPHEN D. KENT.
